COVERING ELEMENT

Alfred B. Walton, Kenmore, N. Y., assignor to
 Certain-Tee Products Corporation, New York,
 N. Y., a corporation of Maryland

Application July 23, 1936, Serial No. 92,102

11 Claims.

(Cl. 108—7)

This invention relates to roofing elements, such as shingles, and more particularly to shingles intended to be laid on a roof in courses with the shingles positioned with their edges in diagonal relation to the line of the course.

Many shingles of the type referred to above have been proposed and shingles of generally quadrilateral rectangular form have been laid in the roof with the side edges thereof extending at an angle, and usually at equal angles and in many cases substantially at an angle of 45°, with the line of the horizontal courses of shingles. Provision has been made for overlapping shingles laid successively in a direction upwardly along the roof so as to produce a weather-tight construction. Tongues also have been provided extending outwardly of the shingle to provide a means for fastening the shingle to the roof. Many peculiar shapes of shingles have been proposed in order to provide means for interlocking one shingle with the edges of the adjacent shingles.

The present invention provides a shingle of generally quadrilateral, parallelogram or rectangular form having a tongue extending outwardly of the shingle adjacent one of the corners which is to be laterally positioned, that is, substantially in the line of the course with respect to the diagonally opposite corner of the shingle. This tongue is so formed as to provide a substantial area extending beyond the corner of the quadrilateral, that is, beyond the meeting points of the corners of adjacently positioned shingles, or their quadrilaterals, in the horizontal course. The form of this tongue is such as to provide an outer end edge on the tongue of substantial extent and to provide a tongue of substantial width in the direction transversely of the course so that a nail or fastening device may be positioned so as securely to hold down the tongue and the shingle while being adequately covered by the overlapping course of shingles to prevent water entering the roof around the fastening.

Moreover, the tongue is so formed and is positioned with respect to the body of the shingle that this tongue may be nailed or fastened securely upon the supporting structure but at such a distance upon the tongue from the body of its shingle that an auxiliary fastening means, such as a rivet or clamp or staple or any of the common devices for fastening two overlapping shingles together, may be inserted and fastened in place between said nail and the body of the shingle from which said tongue extends. This

insertion may be made after the overlapping superjacent shingle is fastened in place because the tongue provides sufficient material between the nail and the body to permit such insertion and the insertion of the riveting or clamping tool if required.

The invention also provides for so forming a notch in the corner of the shingle diagonally opposite to the tongue that the shingles may readily be laid in the horizontal courses on the roof, the notch serving to guide the laying by fitting to the tongue of the shingle adjacent in the course.

The outline of the tongue and of the notch in the shingle of the invention are such that portions of this outline and points thereon may be used as guides in the laying of the shingles in the superjacent course. Moreover, the outline of the tab and of the notch are such that the shingles may be cut from a sheet without waste in the forming of the tongues, the shingles at either side of the severing cuts being of like form.

The shingle, at the corners thereof which are on the diagonal extending transversely of the horizontally extending diagonal, may be made of truncated form or with other outline to produce modifications of the generally quadrilateral or diamond motif in the assembled shingles in the roof construction. Preferably, the corner which is to be positioned lowermost in the roof construction is made of similar outline or of similar extent to the lower edge of the tongue of the same shingle so that said lower edge of the tongue may serve as a means for positioning the shingle in a superjacent course to provide for the desired overlap of said superjacent shingle upon both of the two adjacent shingles in the subjacent course. The outlines of the tongue and of the recess are so related to the adjacent corners of the adjacent shingles in a course that by superposing the truncating edge of a superjacent shingle upon said lower edge of the tongue the proper degree of "headlap" is secured.

The invention further includes the process of producing shingles of the type which has been referred to above, particularly the process of forming the tongues and the truncated edges without waste of the material of the sheet from which the shingles are cut.

The invention will be more clearly understood from the following description taken in connection with the drawing in which

Figure 1 shows the shingle element of the invention;

Figure 2 shows an assembly of the shingles of Figure 1; and

Figure 3 shows the process of cutting the shingles of the invention from a sheet of material. The invention is illustrated in Figure 1 by a shingle of generally rectangular outline, in the particular embodiment of square form. From the body 1 of the shingle, adjacent the righthand corner 2 of the rectangle which would be formed by its edges 6 and 7 if continued, extends the tongue 3. This tongue is formed with the lower edge 4 extending horizontally, that is, on a line parallel to the diagonal of the square, this diagonal being that which will be positioned in the generally horizontal line of a course in the assembly of shingles. The upper edge 5 of the tongue 3 is formed in sloping relation to the lower edge 4 and passes through the corner 2 of the rectangle. The edge 5 is not coincident with either of the lines 6 and 7 of the rectangle which forms the corner 2 thereof. By thus forming the upper edge 5 of the tab 3 in a sloping relation to the lower edge 4 while at the same time not making this edge 5 coincident with the edge 7 of the shingle, a tongue of greater width at the inner end thereof is secured and greater strength of the tongue thus provided.

Moreover, the tongue 3 may be formed with its outer end edge 8 transverse to the edges 4 and 5 of the tongue to form a blunt end of the tongue. As will be understood from the description hereafter to be given in connection with the process of producing the shingles of the invention, by thus forming this blunt edge 8 on the tongue and also in making the edge 5 not coincident with the edge 7 of the rectangle, the edge 10 of the shingle connecting the edge 1 with the edge 5 may be made of like form and extent with the end edge 8 of the tongue. While this will permit cutting shingles from the sheet without waste, ample area is provided in the tongue 3 so that a nail or other fastening device 68 may be positioned, as shown in Figure 2, beyond, that is, toward the right of, the corner 2 of the rectangle and sufficiently removed from the edge 4 of the tongue to insure that the lower edge 12 of an overlapping shingle properly will cover the fastening 68 and prevent the water entering the roof around the fastening.

At the left hand corner of the shingle of Figure 1, which is diagonally opposite the tongue 3 is shown a notch formed by the edges 14 and 15. The corner 13 of the shingle formed between the edge 15 and the edge 16 is the corner of the rectangle formed by the intersection of the edges 16 and 18 extended. The edge 14, however, is of like form and extent to the end edge 8 of the tongue 3 and the edge 15 is of like form and extent, and in like angular relation to the edge 14, as is the portion 9 of the edge 5 which lies between the corner 2 of the rectangle and the end edge 8 of the tongue, said corner in the embodiment illustrated being upon the line 5 substantially at the mid point thereof. It will thus be clear that when two shingles of the type illustrated in Figure 1 are assembled as in Figure 2 the tongue 3 may have its end edge 8 and the portion 9 of the edge 5 thereof fitted to the edges 14 and 15 respectively of the laterally adjacent shingle in the course.

As the edge 12 which truncates the corner of the rectangle formed by the edges 18 and 6 may be made of like extent and in like angular relation to the edges of the rectangle as is the lower edge 4 of the tongue 3, a shingle of like form may be positioned in a superjacent course relative to the shingles of a subjacent course by

bringing the edge 12 thereof in coincidence with the edge 4 of the tongue of the subjacent shingle. As the edge 4 of the tongue is formed below the corner 2 of the rectangle at which the edges 6 and 7 of the shingle intersect, in view of the like extent of the edges 12 and 4 of their like angular relation to the edges of the rectangle, the "headlap" of said superjacent shingle is thus determined by bringing the edge 12 into coincidence with the edge 4 of the subjacent shingle. Moreover, when, as illustrated in the particular embodiment shown in Figure 1, the edges 12 and 4 are formed at 45° with the edges of the square of the shingle itself, like overlap, that is, like headlap, will be produced on the two subjacent shingles when the superjacent shingle is positioned with the edge 12 coincident with the edge 4 of the tongue of the subjacent shingle.

As will be clear from Figure 2, when the tongue 3 is fitted to the notch of the adjacent shingle, the corner 13, being the corner of the rectangle, will meet the corner of the rectangle of the lefthand shingle, the point 2 of which corner is positioned on the edge 5 of the tongue 3. If desired, this point 2 may be marked on edge 5 by suitable means. In view of the equiangular relation of the edge 4 to the edges 6 and 18 of the two laterally adjacent shingles and because the tongue 3 of the lefthand shingle fits to the notch of the righthand shingle, the edge 4 meets the edge 18 of the shingle at such a point that the corner 13 is equidistant from said meeting point and from the intersection of the edge 4 with the edge 6 of the lefthand shingle. Likewise the edge 14 of the notch intersects the edge 18 at said first meeting point. It will be seen from Figure 2 that in view of the relation of the edges described, the edge 16 of the righthand shingle is in line with the edge 6 of the lefthand shingle.

In the particular embodiment illustrated, these distances from the corners 13 and 2 may be, for example, 2.475" in order that the tongue may be formed with the edge 4 of a length of 3½". Thus the superjacent shingle will overlap each of the subjacent shingles substantially 2.475". It will be clear from a study of the drawing, with these dimensions in mind, that if the outer edge 8 of the tongue 3 is made with the dimension of 1⅓", the inner width of the tongue may be 2⅓". The edge 10, therefore, may likewise be 1⅓", the total extent of this partially truncated corner being 3½", including the base width of the tongue.

The dimensions which have been given above are typical of a shingle which may be 16" square, but the invention is not limited to these particular dimensions. Modifications, both of the particular dimensions above given and of the dimensions of the rectangle, so that one dimension thereof is longer than the other, may be made. Moreover, the shingle may be made with similar dimensions or proportions but of parallelogram form.

It will now be understood that with a shingle of such size or proportions having the tongue formed as described it is possible to insert a rivet or similar fastener 10 to hold the superjacent shingle down to the tongue 3 of the subjacent shingle and that this rivet or fastener 10 may be so inserted after said tongue 3 has been nailed or fastened, as at 68 of Figure 2, to the supporting structure.

The upper corner of the shingle, as illustrated in Figure 1, also may be truncated with an edge 75

in like relation to the sides of the rectangle as is the lower truncated corner. From Figure 2 it may be seen that the corner 60 may provide an additional guide for laying the shingle in correct relation to the shingle previously laid in a subjacent course, by bringing the corner 60 formed by the edges 7 and 10 into coincident position upon the corner 62 formed by the upper truncating edge and the edge 16 of the subjacent shingle.

10 The shingle being laid also may be positioned in correct angular or rectangular relation to the shingle of the subjacent course and to the other shingles in its own course by utilizing this means of guiding the laying together with that provided by bringing the edge 16 of the shingle being laid into coincident position upon the corner 64 formed by the top truncating edge and the edge 7 of the subjacent shingle.

In Figure 3 is illustrated the process of producing shingles of the type illustrated in Figure 1 by cutting a sheet, for example of 32" width, longitudinally thereof with cuts 30 which are spaced lengthwise thereof so that the adjacent ends 32 and 33 in the adjacent cuts are separated. 20 Transversely of the sheet, and of the cuts 30, cuts 35 are formed in the sheet with the adjacent ends 36 and 37 of adjacent cuts spaced apart. The cuts 30 and 35, however, are made on lines which intersect in a common point 38, this common point being that at which the corners of the rectangles of the shingles being cut from the sheet would meet if the sides of the rectangle were extended. Preferably the ends of the cuts 32, 33, 36, 37 are equidistant from the 25 common point 38. Within the scope of the invention, however, these distances may be varied if the tongues are made of different outline or if it is desired to make the tongues on the different shingles being cut in this process in different relation to each other.

40 Through the common point 38 a cut 40 is made which it will be recognized will form the edge 5 of the tongues 3. Preferably the cut 40 extends equal distances either side of the common point 38. Connecting at the ends of the cut 40 are cuts 42 and 43 which respectively connect to the ends 36 and 37 of adjacent transverse cuts 35. The cut 40 is formed so as to be not coincident with the line upon which the cuts 35 are formed. It will be understood that in view of the angular relation of the line 40 to the line of the cuts 35 the tongues 3 on the two shingles which are diagonally related at the common point 38 may be formed with the blunt ends 8, and the tongues 3 may be of like or similar form. In order to complete the tongues in such outline as to extend outwardly of the shingles adjacent the corner thereof and in the general direction parallel to the diagonal of the rectangle, the cuts 44 and 45 45 are formed to produce the lower edge 4 of the tongues on each of said two diagonally positioned shingles in the sheet being cut. It also will be clear that the cuts 44 and 45 form the truncated lower corners of the two other shingles diagonally related in the sheet at the common point 38.

50 Thus the cuts 40, 42, 43, 44, 45 taken together substantially are of S form extending as a continuous line between the ends 32 and 33 of the longitudinal spaced cuts 30. While the outline of this S in the particular embodiment illustrated consists of a succession or set of straight lines, it will be understood that the invention likewise includes the making of a cut of S form drawn as a curve between the ends 32

and 33 and touching the ends 36 and 37. Said curve also may pass through the common point 38. It is a feature, therefore, of the process of the invention that a cut of S form is made in the sheet, that cuts are formed extending in generally opposite directions from the ends of the S and at an angle to the usual upright line of the S as ordinarily viewed, and that cuts are also formed transversely to said first mentioned cuts and extending from the bends of the S in opposite directions to each other. Thus it will be clear that from a sheet of material elements may be cut which have tongues extending outwardly thereof adjacent the corners thereof in a direction generally that of the diagonal of the elements to said corners.

In the particular embodiment shown elements of generally square form are cut from the sheet, the length of the cuts 35 and 30 being substantially equal. At the ends of the cuts 35 which are removed from the S cut, in order to form the notches in the elements, cuts in the sheet along the lines 50, 51 and 52 are formed to remove pieces of material from the sheet. It will be clear that by removal of this piece of material at each side edge of the sheet not only are the edges 14 and 15 formed in the shingle respectively by the cuts 51 and 50 but the upper corners of the two adjacent shingles in the sheet are truncated by the cut 52.

40 While by removal of these pieces of material a certain amount of waste is produced, nevertheless the process of the invention makes it possible to produce the shingles with little waste and less than would be necessary if the tongues were formed in a different relation than that secured by the formation of the S cut in the sheet. By repeating the formation of the S cut at spaced points along the length of the sheet and correspondingly forming the cuts 30 as well as the transverse cuts 35 and the cuts 50, 51 and 52, a series of shingle elements may be cut from the sheet. If desired the cuts 50 and 51 only may be made in the sheet adjacent the edges thereof, as extensions of the cuts 35, to complete the severing of the shingles from each other. In such case the shingles will have a projection between the corner 62 and the corner 64 instead of the truncating edge at the upper corner. In such case no material will be removed from the sheet.

55 The invention is not limited to the particular square or rectangular form of element illustrated and variations from this form may be made within the scope of the invention while retaining the features which have been described. Likewise the process may be applied to the production of shingles of different shapes having tongues extending from the corners thereof.

Having thus described my invention I now claim:

1. A shingle of generally quadrilateral shape having a tongue extending outwardly of the shingle from a corner thereof in the direction generally like-extending with the diagonal to 65 said corner, said tongue extending beyond the point determining said corner of the quadrilateral and being of substantial width throughout said extent to provide a substantial area of the tongue beyond said point for a fastening applied to said tongue.

2. A shingle of generally quadrilateral shape having a corner of the quadrilateral truncated and having a tongue extending outwardly of the quadrilateral from a corner thereof other than 75

the corner opposite said truncated corner, said tongue having two edges thereof extending in the direction generally parallel to said truncating edge and beyond the point determining said edge and beyond the point determining said 5 other corner a distance sufficient to provide beyond said corner a substantial area of the tongue for a fastening applied thereto, said tongue having the edge on the side thereof toward said truncated corner substantially parallel to said 10 truncating edge.

3. A shingle of generally quadrilateral shape having a corner of the quadrilateral truncated and having a tongue extending outwardly of the quadrilateral from a corner thereof other than 15 the corner opposite said truncated corner, said tongue having two edges thereof extending in the direction generally parallel to said truncating edge and beyond the point determining said other corner a distance sufficient to provide beyond said corner a substantial area of the tongue for a fastening applied thereto, said tongue having the edge on the side thereof toward said truncated corner approximately equal to that 20 of said truncating edge.

25 4. A shingle of generally quadrilateral shape having a tongue extending outwardly of the shingle from a corner thereof in the direction generally like-extending with the diagonal to said corner, said tongue having a substantial extent in said direction beyond the point determining said corner of the rectangle so that a portion of said tongue lies between the extensions of the sides of the quadrilateral which form said corner, said shingle having therein adjacent 30 the corner at the opposite end of said diagonal a notch of similar outline to at least a part of the outline of the tongue and so positioned with respect to the adjacent corner as to provide space for a similar tongue of an adjacent shingle 35 of an assembly fitting to said notch and to determine the spacing of said shingles.

5. A shingle of generally parallelogram shape having two opposite corners truncated in substantially like-relation to the edges of the shingle, said shingle having a tongue adjacent and 45 extending a substantial distance outwardly from one of the other corners so that a portion of said tongue lies between the extensions of the sides of the parallelogram which form said corner, said shingle being notched adjacent the fourth corner 50 to fit to a similar tongue of a similar shingle to position said shingles with the edges thereof in generally parallel relation.

6. A shingle of generally parallelogram shape 55 having a corner thereof truncated to form an edge to be exposed, said shingle having adjacent another corner other than the corner diagonally opposite to said truncated corner a tongue extending generally diagonally outwardly of the shingle beyond said adjacent corner, said tongue 60 having an edge on the side thereof toward said truncated corner substantially parallel to and substantially equal to the truncating edge of said first corner, said tongue having an edge thereof on the far side thereof from said truncated corner extending out of alignment with the line of a side of the parallelogram or an extension thereof to increase the width of the outer portion of said tongue.

70 7. A shingle of generally parallelogram shape having a tongue adjacent one corner of the parallelogram formed with an edge thereof passing through said corner of the parallelogram but out of alignment with a side of the parallelogram 75 or an extension thereof, said edge being gen-

erally like-extending with the diagonal to said corner of the parallelogram, said tongue having another edge thereof generally like-extending with said diagonal of the parallelogram to said corner and removed from said corner in the direction of the exposure of the shingle a distance to provide a tongue of substantial width transverse to said diagonal, said tongue being of sufficient length beyond said corner to provide in consideration of said width sufficient area 10 within its outline for a fastening securely to hold said tongue upon the supporting structure and to provide between the position of said fastening device and the body of the shingle for a clamping or riveting device to hold an overlapping shingle down to said tongue.

8. A shingle of parallelogram shape having a corner thereof truncated at a predetermined angle to an adjacent side of the parallelogram, said shingle having a tongue extending outwardly of the parallelogram adjacent the corner which is at the other end of said side of the parallelogram from said truncated corner, said tongue having the edge thereof which is nearer said truncated corner substantially equal to said 25 truncating edge and in similar angular relation to said side of the parallelogram as is said truncating edge, said tongue having the edge outline thereof which is at the far side of said tongue from said truncated edge symmetrical about the 30 point determining said corner of the parallelogram adjacent which said tongue is positioned and out of alignment with an edge of the parallelogram or an extension thereof to increase the width of the outer portion of said tongue. 35

9. A shingle of generally square shape having a corner thereof truncated by an edge of given outline between two adjacent sides of the square, said shingle having adjacent a corner other than that opposite said truncated corner a tongue 40 extending outwardly beyond said corner of the square and formed with an edge on the side thereof toward said truncated corner substantially equal and parallel to said truncating edge, said tongue having the other edges thereof 45 formed on a line of substantially symmetrical outline extending from the outer end of said parallel tongue edge to a point on the third side of the square adjacent said tongue, said outline passing through said corner of the square adjacent said tongue but being out of alignment with said third edge of the square, said shingle having a notch therein adjacent the corner diagonally opposite said tongue, said notch being formed in an outline parallel to and equal to that portion of said other edge of said tongue between said outer end of the parallel edge thereof and said corner of the square adjacent the tongue, said notch forming edge extending through said corner of the square opposite to 50 said tongue.

10. A shingle of generally parallelogram shape having one corner of the parallelogram truncated symmetrically with respect to the adjacent sides of the parallelogram, said shingle 55 having a tongue extending outwardly therefrom adjacent a corner of the parallelogram other than that opposite said truncated corner, the side of said tongue remote from said truncated corner and the body of the shingle adjacent thereto being formed in an outline out of alignment with and intersecting the side of the parallelogram which is adjacent said tongue but on the far side of the parallelogram from said truncated corner, the point of said intersection being sub- 70 75

stantially the same distance from said corner of the parallelogram at which the tongue is positioned as are the ends of the truncating edge from the corner of the parallelogram which said edge truncates.

5 11. A shingle as in claim 10 in which the corner of the parallelogram opposite said truncated corner also is truncated in like relation to the

sides of the parallelogram adjacent thereto as is said first truncated corner to its adjacent sides so as to provide at each end of the truncating edge a point as a mark for coincidence of the far edge of the adjacent shingle laid on a superposed 5 course.
